DESIGN FOR A LAP-ENGAGING CHILD'S CHAMBER

Neva R. Deardorff, New York, N. Y.

Application February 18, 1946, Serial No. 126,663

Term of patent 7 years

(Cl. D4—5)

To all whom it may concern:

Be it known that I, Neva R. Deardorff, a citizen of the United States, residing at New York, in the county of New York, State of New York, have invented a new, original, and ornamental Design for Lap-Engaging Child's Chamber, of which the following is a specification, reference being had to the accompanying drawing, forming a part thereof, wherein—

Fig. 1 is a side elevational view of a lap-engaging child's chamber showing my new design.

Fig. 2 is a top plan view thereof.

Fig. 3 is an end elevational view thereof.

I claim:

The ornamental design for a lap-engaging child's chamber, as shown.

NEVA R. DEARDORFF.
